UNITED STATES PATENT OFFICE.

THOMAS HARRISON, OF WESTON, ONTARIO, CANADA.

NUTCRACKER.

1,367,384.

Specification of Letters Patent.

Patented Feb. 1, 1921.

Application filed March 27, 1920. Serial No. 369,308.

To all whom it may concern:

Be it known that I, THOMAS HARRISON, of Weston, in the county of York, Province of Ontario, Canada, have invented certain new 5 and useful Improvements in Nutcrackers, of which the following is a specification.

This invention relates to household nut crakers, and my object is to devise an efficient implement which will be simple in construction and yet quickly adjustable to operate on nuts of any size.

I attain my object by means of the constructions hereinafter described and illustrated in the accompanying drawings in 15 which—

Figure 1 is a plan view of a pair of nut crackers constructed in accordance with my invention;

Fig. 2 a side elevation of the same, partly 20 in section, showing the parts in position ready to crack a nut; and

Fig. 3 a similar view showing the parts in the position they assume with the nut cracked.

25 In the drawings like numerals of reference indicate corresponding parts in the different figures.

1 is the handle provided at one end with the post 2 extending up substantially at 30 right angles thereto, and preferably of rectangular cross section, its thickness being preferably considerably less than its width. One transverse side of this post has teeth 3 formed thereon, preferably of ratchet form, 35 the teeth facing toward the handle. These teeth are preferably formed at the inner transverse side of the post.

The handle 4 has a slot formed therein through which the post passes, the slot being 40 substantially the same width as the thickness of the post and somewhat longer than the breadth of the post. At one end of the slot (in the construction shown, the inner end) is formed a tooth 5 adapted to interengage with the teeth and the post. By moving the handle 4 longitudinally the tooth 5 may be 45 disengaged from any given tooth and re-engaged with any other tooth, so that the handles may be suitably spaced to suit the 50 size of the nut being cracked.

The handle 4 is provided with a projection 6 adapted to engage the side of the post opposite the toothed side to limit the rocking movement of the handles toward one another. Preferably the outer end of the han-

dle 4 beyond the slot is upwardly bent and the projection 6 formed on the end thereof.

To avoid accidental disengagement of the tooth 5 from that one of the teeth 3 with which it may be engaged, I provide a spring 60 engaging the handle 4 and the post 2 tending to draw the tooth 5 against the post. In the preferred arrangement I employ a bent spring 7, which is suitably secured to the outer end of the handle 4 and is bent up 65 through the slot to engage the back of the post 3. The opposed faces of the handles adjacent the post are preferably provided with rugosities 8 as is usual to give them a suitable grip on the nuts being cracked. 70

To prevent the handle 4 being removed and lost I provide the post 2 with a pin 9, which prevents the handle sliding off the post.

From the construction described it will 75 be seen that I have devised a nut cracker which will be very efficient, simple in construction, and which may be very quickly adapted to the diameter of the nut to be cracked, which gives it an important advantage over the ordinary cracker and in 80 which two adjustments only are provided.

What I claim as my invention is:—

1. A nut cracker comprising a handle having a post formed at one end of rectangular section and provided with a series of teeth on the inner transverse side; a second handle having a slot formed therein through which the post passes, the slot being of substantially the same width as the thickness of the 90 post and somewhat longer than the breadth of the post; a tooth formed at the inner end of the slot adapted to interengage with the teeth on the post; an upwardly turned projection on the outer end of the slotted handle 95 adapted to engage the side of the post opposite the toothed side to limit the rocking movement of the handles toward one another; and a spring engaging the slotted handle and the post tending to hold the tooth 100 on said handle in engagement with the toothed side of the post.

2. A nut cracker comprising a handle having a post formed at one end of rectangular section and provided with a series of teeth on the inner transverse side; a second handle having a slot formed therein through which the post passes, the slot being of substantially the same width as the thickness of the post and somewhat longer than the 110

breadth of the post; a tooth formed at the inner end of the slot adapted to interengage with the teeth on the post; and an upwardly turned projection on the outer end of the slotted handle extending above the handle adapted to engage the side of the post opposite the toothed side to limit the rocking movement of the handles toward one another.

10 3. A nut cracker comprising a handle having a post formed at one end of rectangular section and provided with a series of teeth on the inner transverse side; a second handle having a slot formed therein through which the post passes, the slot being of substantially the same width as the thickness of

the post and somewhat longer than the breadth of the post; a tooth formed at the inner end of the slot adapted to interengage with the teeth on the post; an upwardly turned projection on the outer end of the slotted handle adapted to engage the side of the post opposite the toothed side to limit the rocking movement of the handles toward one another; and a bent spring secured to the outer end of the slotted handle and extending up through the end of the slot in engagement with the adjacent side of the post. 20 25

Signed at Toronto, Canada, this 11th day of March, 1920.

THOMAS HARRISON.
